R. B. HILTZ

CONTROL FOR SLIDING DOORS

Filed March 19, 1926

*Inventor,
Robert Bruce Hiltz
By, Frederick C. Bromley
Attorney.*

UNITED STATES PATENT OFFICE.

ROBERT BRUCE HILTZ, OF KITSCTY, ALBERTA, CANADA.

CONTROL FOR SLIDING DOORS.

Application filed March 19, 1926. Serial No. 95,943.

The invention relates to improvements in controls for sliding doors as described in the present specification and shown in the accompanying drawing which forms part of 5 the same.

The invention appertains more particularly to sliding doors of grain elevators but is susceptible of being applied to sliding doors of other buildings if so desired.

10 In receiving loads of grain at an elevator the attendant usually weighs the load and then opens a pair of sliding doors in order to allow the vehicle to drive out of the elevator. As these doors are situated some distance from the weighing scales the attendant expends a great deal of time and effort in traversing the distance between the scales and these doors upon each occasion that a load is handled.

20 It is, therefore, the object of the present invention to devise a control which may be situated in the vicinity of these scales by which the operator may open and close the doors in order to save running back and forth, resulting in the expediting of the unloading of the grain to the elevator.

The invention consists substantially of a large and small sheave having ropes extending therefrom and passing over pulleys and 30 connecting to a pair of sliding doors, the ropes being so arranged that upon turning the sheaves in one direction the doors will be opened and in turning them in the opposite direction will be closed.

35 The drawing is a perspective view of an elevator driveway showing a pair of sliding doors and the invention applied thereto.

In the drawing, the reference numeral 1 indicates the driveway and 2 and 3 a pair of sliding doors which operate to and from each other edgewise. These doors are usually known either as "sliding" or "rolling" doors.

40 4 is an overhead rail upon which the doors are suspended by hangers as at 5. Situated at some little distance from the doors, rotatably journalled on the side-wall 6 is a large sheave 7 carrying a handle 8 and to one side of this sheave is a comparatively small sheave 9 integral with or secured thereto in any convenient manner.

45 50 10 is a rope secured to the small sheave 9

and passing around its periphery to a pulley 11 from which it is extended to the door 2 and secured as at 12 near its abutting 55 edge 13.

14 is a rope affixed to the sheave 7 and passing therearound in a contrary direction to the rope 10. This latter rope extends to a pulley 15 and from there to a further pulley 16 attached to the door 3 and is then returned to the door 2 to which it is affixed as at 17.

18 is a rope connected to the door 2 and extending therefrom to a pulley 19 and returned to the abutting edge 20 of the door 3 and secured thereabouts.

In the operation of this invention, to open the doors it is merely necessary to revolve the sheaves by means of the handle 8 in a 70 direction to wind the rope 10 on the sheave 9, thus pulling upon the door 2 and opening same.

As the rope 10 winds about the sheave 9, the other rope 14 unwinds from the larger 75 sheave 7 at a greater speed and thus slackens sufficiently to permit of the door 3 opening. As the door 2 is opened it opens the door 3 by means of the rope 18 passing over the pulley 19. To close the doors, the sheaves 7 80 and 9 are turned in the opposite direction thus winding the rope 14 on the sheave 7 and closing the doors while the rope 10 is unwound in order to permit the door 2 to close. It will be evident from what has preceded 85 that the sheaves 7 and 9 will have to be so relatively proportioned that their ropes will travel at their correct speed ratio.

What I claim is:—

The combination with a pair of sliding 90 doors, of a small and a large sheave affixed to each other, a flexible element circumferentially extending from each of said sheaves and affixed to one of said doors, said flexible elements being arranged for oppositely 95 winding on their sheaves, one of said flexible elements being passed around a pulley carried by the other door, and means operated by one of the doors for opening the other door.

Signed at Kitscoty, Alberta, Canada, the 100 25th day of February, 1926.

ROBERT BRUCE HILTZ.
